DESIGN FOR A COMBINED CHAIR AND MAGAZINE RACK

Gerhard R. Schutes, Saginaw, Mich., assignor
to Spartan Aircraft Company, Tulsa, Okla.

Application November 27, 1945, Serial No. 124,094

Term of patent 3½ years

(Cl. D15—1)

To all whom it may concern:

Be it known that I, Gerhard R. Schutes, a citizen of the United States, residing at Saginaw, in the county of Saginaw and State of Michigan, have invented a new, original, and ornamental Design for Combined Chair and Magazine Rack, of which the following is a specification, reference being had to the accompanying drawing, forming part thereof.

In the drawing:

Fig. 1 is a perspective view of a combined chair and magazine rack showing my new design.

Fig. 2 is a side elevational view.

Fig. 3 is a front elevational view of the same.

I claim:

The ornamental design for a combined chair and magazine rack, as shown.

GERHARD R. SCHUTES.
